US00D642520S

(12) **United States Design Patent**
Chun et al.

(10) **Patent No.:** **US D642,520 S**
(45) **Date of Patent:** **** Aug. 2, 2011**

(54) **CRADLE FOR CHARGING TABLET COMPUTER**

(75) Inventors: **Bum-Ho Chun, Seoul (KR); Sang-Sung Woo, Seoul (KR)**

(73) Assignee: **Samsung Electronics Co., Ltd., Kyunggi-do (KR)**

(**) Term: **14 Years**

(21) Appl. No.: **29/372,409**

(22) Filed: **Nov. 16, 2010**

(51) LOC (9) Cl. **13-02**

(52) U.S. Cl. **D13/108**

(58) Field of Classification Search **D13/107-110, D13/118-119, 184, 199; D14/251, 253, D14/432, 434; 320/107-115**

See application file for complete search history.
